UNITED STATES PATENT OFFICE.

JOHN FRASER, OF MILWAUKEE, WISCONSIN.

GYRATORY MACHINE.

948,047.

Specification of Letters Patent. Patented Feb. 1, 1910.

Application filed June 18, 1906. Serial No. 322,149.

To all whom it may concern:

Be it known that I, JOHN FRASER, a citizen of the United States, residing at Milwaukee, in the county of Milwaukee and State of Wisconsin, have invented certain new and useful Improvements in Gyratory Machines, of which the following is a specification, reference being had to the accompanying drawing, forming a part thereof.

10 This invention relates to machines such as bolting or screening machines, concentrators and the like, of the class shown and described in United States Letters Patent No. 756,950, dated April 12, 1904, and No. 15 758,907, dated May 3, 1904, which have freely suspended gyratory parts provided with vertical eccentrically weighted rotary shafts.

The main objects of the present invention are to automatically vary the distance of the eccentric weights from the axis of rotation so as to gradually increase and decrease the amplitude or extent of the gyratory movement of the machine in stopping and starting, 25 to quickly bring the moving parts to their normal gyratory circuit around a fixed axis as they attain normal speed in starting, and to rest in stopping without shock or jar; and generally to improve the construction and 30 operation of machines of this class.

It consists in certain novel features of construction and in the peculiar arrangement and combination of parts as hereinafter particularly described and pointed out in the 35 claims.

In the accompanying drawing like characters designate the same parts in both figures.

Figure 1 is a central vertical section of a 40 gyratory bolting machine embodying the present invention, the sieves being omitted, and Fig. 2 is a plan view of one of the yielding centrifugal weights for varying and regulating the gyratory movement of 45 the machine in stopping and starting.

Referring to Fig. 1, *a* designates the case or frame of the bolting machine, which is freely suspended by jointed or flexible hangers *b* from an overhead support *c*, and is 50 provided at the center with bearings *d*, for a vertical rotary shaft *e*. This shaft is provided with a pulley *f*, which is connected by a belt *g* running on guide pulleys *h* attached to the case or frame *a*, with a suitably located driving pulley, not shown. With the 55 shaft *e* are connected so as to partake of its

rotary movement, one or more weights *i*, in the present instance one above and another below the case or frame *a*. These weights are movable radially or toward and from the shaft *e*, and their outward movement is opposed by yielding resistances, in the present instance springs *j* connecting said weights with the inner ends of horizontal frames or arms *k*, which support them and are fixed on the shaft *e*. These frames or arms are provided with parallel guide rods *l*, upon which the weights are mounted and freely movable radially with relation to said shaft, the outer ends *m* of said frames or arms serving as stops to limit the outward movement of the weights. The springs *j* are shown as adjustably connected with the weights by threaded bolts *n* provided with nuts for regulating the tension of the springs and varying the position of the weights with 75 relation to the shaft *e*.

The machine operates as follows: In starting, the weights being held by the springs *j* at the inner limits of their movement, or close to the shaft *e* as shown in the drawing, have the least centrifugal effect upon the shaft *e*, which tends to rotate about its own axis, but as the speed of the shaft increases, the weights are gradually moved away from it against the tension of the springs by increasing centrifugal force, and as they move outwardly, their centrifugal effect on said shaft increases, causing it, with the loosely suspended case or frame in which it turns, 85 to gyrate in a gradually enlarging circuit. When the shaft *e* attains its full normal speed, the outward movement of the weights is arrested by the springs or by the stops *m*, and the case or frame *a* with its load gyrates 90 about its center of gravity, which is determined or modified by the position of the weights. In moving away from the shaft *e* as its speed increases, the weights *i* gradually shift the center of gravity of the machine away from the axis of the shaft *e*, thereby gradually increasing its gyratory orbit or circuit and avoiding the erratic movements and consequent shock and jar to the machine and its supporting connections 100 which would take place if the weights were permanently set to produce the normal gyratory circuit and the shaft *e* was unconfined. In stopping, as the speed of the shaft *e* and the centrifugal force of the weights *i* 105 are reduced, said weights are gradually moved inwardly by the springs toward said

shaft, thereby diminishing their centrifugal effect thereon and consequently the gyratory orbit or circuit of the machine until it finally comes to rest, the weights assuming their initial positions, as shown in the drawing.

The construction and arrangement of the shifting weights, their connections with the shaft *e* and the springs or yielding resistances may be modified in various ways without materially affecting their mode of operation and without departing from the principle and intended scope of the invention.

I claim:

1. In a gyratory machine the combination with a freely suspended member capable of gyratory movement in an approximately horizontal plane, of a vertical rotary shaft centrally journaled in said member and provided with a radially disposed guide having a stop, a weight movably mounted on said guide between said shaft and stop, and a spring located on the opposite side of the weight from the stop and tending to move the weight toward said shaft, substantially as described.
2. In a gyratory machine the combination with a freely suspended member capable of gyratory movement in an approximately

horizontal plane, of a vertical rotary shaft centrally journaled in said member and provided with a radially disposed guide having a stop, a centrifugal weight movably mounted on said guide between said shaft and stop, a spring tending to move said weight toward said shaft, and means for adjusting the tension of said spring independently of said stop, substantially as described.

3. In a gyratory machine the combination with a freely suspended member capable of gyratory movement in an approximately horizontal plane, of a vertical rotary shaft journaled centrally in said member and provided adjacent to its upper and lower ends with radially disposed guides having stops at their outer ends, centrifugal weights movably mounted on said guides between said shaft and stops, and springs located on the opposite sides of the weights from the stops and tending to move the weights toward said shaft, substantially as described.

In witness whereof I hereto affix my signature in presence of two witnesses.

JOHN FRASER.
